UNITED STATES PATENT OFFICE.

WILLARD H. KEMPTON, OF MANSFIELD, OHIO, ASSIGNOR TO THE OHIO BRASS COMPANY, OF MANSFIELD, OHIO, A CORPORATION OF NEW JERSEY.

OVERHEAD-TROLLEY APPARATUS.

1,123,551.

Specification of Letters Patent.

Patented Jan. 5, 1915.

Application filed February 26, 1912. Serial No. 679,844.

To all whom it may concern:

Be it known that I, WILLARD H. KEMPTON, a citizen of the United States, residing at Mansfield, in the county of Richland and State of Ohio, have made new and useful Improvements in Overhead-Trolley Apparatus, of which the following is a specification.

My invention relates to overhead apparatus for electric railways, and has more particular reference to apparatus of the kind generally known as frogs, crossings, and like devices, to which the trolley wire is attached.

One of the objects of my invention is to provide an improved device which will be extremely simple and durable in construction, and effective and efficient in operation.

Another object of my invention is to provide an improved trolley frog embodying a member to which the trolley wire is attached, and a wear member or extension detachably interlocked therewith without the aid of separate fastening members, such as screws, bolts, and the like; my object being further to so design these parts that they may be cast ready for installation and use, and to thereby eliminate the necessity of expensive machine work.

To the attainment of these ends, and the accomplishment of other new and useful objects hereinafter appearing, my invention consists in the features of novelty disclosed in the construction, combination and arrangement of parts hereinafter described and claimed, and shown in the accompanying drawing, which illustrates one example of my invention, and in which

Figure 1 is a top plan view of a piece of overhead trolley apparatus commonly known as a frog, wherein my invention is embodied. Fig. 2 is an enlarged view in side elevation of the end portion thereof; Fig. 3 is a perspective view of the detachable tip; Fig. 4 is a bottom plan view of said tip; Fig. 5 is a sectional view on line 5—5 of Fig. 2; Fig. 6 is a sectional view on line 6—6 of Fig. 2.

In the drawing I have illustrated my invention as embodied in a piece of apparatus generally known as a frog, the function of which is generally to form a connecting point in the trolley wire from which a branch wire may be led off. However, it will be obvious to one skilled in the art,

after having obtained an understanding of my invention from the disclosures herein made, that my invention is equally as applicable to overhead apparatus used for other purposes, such, for instance, as section insulators, crossings, splices, and the like.

The body member A of the frog shown in the drawing comprises a single metal casting having laterally projecting loops or eye-lugs 1 to which the cross or supporting wires may be attached. This body casting has a groove or channel 2 for the reception of the main trolley wire 3, and an angularly disposed groove or channel 5 for the branch wire 6. These grooves are generally open at their tops so that the trolley wires may be placed therein, and there is a substantially centrally disposed clamping member 7 for holding the wires in their proper relation. In addition to this there may be provided a clamping device 8 adjacent the outer end of each channel for the purpose of firmly holding the frog in position at these points. These clamps 8 may be of any suitable or usual form for the purpose. The metal adjacent the outer ends of the body casting is preferably substantially U-shaped in section, so that the wire receiving channels 2 and 5 will be comparatively deep at these portions, and the under sides 9 of the metal are round in section to provide smooth under-running surfaces for the trolley wheels carried on the cars.

It will be seen by reference more particularly to Figs. 2 and 5, that there is a more or less thickness of metal 10 beneath the trolley wire at the ends of the channels, and this necessarily would destroy the continuity of the underrunning surface and cause bumps which would likely throw the trolley wheel off. These end parts of the casting would also be the most subjected to the wear incident to the passage of the trolley wheels. These objections are obviated by the provision of wear members or tip extensions B which are renewable at comparatively small expense, and which are also flexible to a degree sufficient to prevent the sharp bending or flexing, and consequent crystallization and breakage of the trolley wire. These tips are preferably substantially U-shaped in cross section, and their lower edges 11 are made bendable so that these edges may be bent around the trolley wire. The inner ends 12 of these tips preferably abut the

ends of body casting, and the metal at these points is practically of the same thickness as that of the adjacent body metal 10. The under metal of the tip members is tapered, so that a gradual or easy approach on to the body casting is provided. The tapering of the tip metal is preferably accomplished by tapering the edges 11 thereof, toward the outer ends 13, as shown in Fig. 4, so that 5 the underrunning surface at the outer end practically merges with the surface of the trolley wire. The interlocking connection, as will be later described, between the tip members and the body member allows the 10 tip members a slight vertical movement with respect to the body member. These tip members add rigidity or stiffness to the portions of the trolley wire which they embrace. Any tendency, therefore, of the trolley wire 15 to make a sharp bend at the end of the body member is thus prevented for the reason that on account of the slight relative movement which the tip members have they distribute the bending action over a considerably 20 greater length of trolley wire and cause the bends to be more gradual, thus effectively overcoming any tendency for the wire to crystallize and break.

The walls 14 of the wire channels rise considerably 25 above the wire in the channels, and, as before mentioned, the channels are open at their tips to permit the entrance of the wire.

Referring to the drawing it will be seen 30 that each tip member or wear member is provided with an inclined extension 15 (preferably integral) which projects beyond the end of the tip and into the space between the walls 14 of the channel. At the end of 35 this extension is a transverse head or cross-bar 16, which extends into a slot or opening 17 in each wall 14. These slots and the head 16 are so formed that the tip must be rotated upward to an angular position in order that 40 the head may be entered into or removed 45 from the slots.

The forward ends 18 of the slots (Fig. 2) 50 form abutments for the head and prevent longitudinal movement of the tip when it is in place, while the overhanging portions 55 lock the head against vertical movement. It is thus seen that an interlock is thus formed which requires no bolts or screws or other fastening devices, and the tips may be

readily removed or replaced. Furthermore, 55 these parts may be formed in the casting and the necessity for a machine work finish is obviated.

It is to be understood that my invention 60 may be modified to meet the requirements of other apparatus wherein my invention 65 may be embodied, without departing from the spirit and scope thereof, and I do not wish to be limited to the particular structure shown in the drawings. 65

What I claim as new is:

1. In apparatus of the class described, the combination of a body member having a trolley wire channel, slots in the walls of 70 said channel, a member attached to the trolley wire in alignment with said channel, an integral extension on said tip, and an integral transverse head on said extension in interlocked engagement with said slots. 75

2. The improvements herein described, 80 comprising a body member having an open top groove adapted to permit a trolley wire to be entered therein, and openings in the side walls of said groove above the trolley wire, in combination with a separate tapered 85 tip member adapted to receive the wire, and having a T-shaped extension projecting between the walls of said wire groove and into interlocked engagement with said openings in the walls of said grooved body member. 85

3. The improvements herein described, 90 comprising a cast metal body member having a U-shaped channel for a trolley wire, the walls of said channel rising above the wire, in combination with a flexible wear 95 member, positioned in alignment with and adjacent the end of said channel, and having tapered bendable lips formed around the trolley wire, openings in the walls of said body and an integral extension on said wear 95 member in interlocked engagement with said openings, and removable therefrom only at an angle to the aligned position of said wear member.

In testimony whereof I have signed my 100 name to this specification, in the presence of two subscribing witnesses, on this 20th day of February A. D. 1912.

WILLARD H. KEMPTON.
